(57) **CLAIM**

The ornamental design for a cutting unit for shaver, as shown and described.

DESCRIPTION

FIG. 1 is a perspective view of a first embodiment showing a cutting unit for shaver according to our design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view of a second embodiment showing a cutting unit for shaver according to our design;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof;

FIG. 14 is a bottom plan view thereof;

FIG. 15 is a perspective view of a third embodiment showing a cutting unit for shaver according to our design;

FIG. 16 is a front elevational view thereof;

FIG. 17 is a rear elevational view thereof;

FIG. 18 is a right side elevational view thereof;

FIG. 19 is a left side elevational view thereof;

FIG. 20 is a front perspective view thereof;

FIG. 21 is a top plan view thereof;

FIG. 22 is a perspective view of a fourth embodiment showing a cutting unit for shaver according to our design;

FIG. 23 is a front elevational view thereof;

FIG. 24 is a rear elevational view thereof;

FIG. 25 is a right side elevational view thereof;

FIG. 26 is a left side elevational view thereof;

FIG. 27 is a top plan view thereof; and,

FIG. 28 is a bottom plan view thereof.

The portions of the cutting unit for shaver shown in broken lines are included for the purpose of illustrating unclaimed portions of the cutting unit for shaver and form no part of the claimed design.

1 Claim, 12 Drawing Sheets
